UNITED STATES PATENT OFFICE.

ELI BROTHERS, OF LYNN, MASSACHUSETTS, ASSIGNOR TO UNITED SHOE MACHINERY CORPORATION, OF PATERSON, NEW JERSEY, A CORPORATION OF NEW JERSEY.

UPPER-PULLING MACHINE.

Application filed July 24, 1918. Serial No. 246,523.

To all whom it may concern:

Be it known that I, ELI BROTHERS, a citizen of the United States, residing at Lynn, in the county of Essex and State of Massachusetts, have invented certain Improvements in Upper-Pulling Machines, of which the following description, in connection with the accompanying drawings, is a specification, like reference characters on the drawings indicating like parts in the several figures.

This invention relates to upper pulling machines, and is herein shown as embodied in a machine particularly designed for pulling an upper preliminarily to stretch it and draw it into approximate conformity to the contour of a last prior to the presentation of the shoe to a pulling-over machine. It will be understood, however, from a consideration of the construction and mode of operation of the illustrative machine that in many of its features the invention is not restricted in utility to machines for thus performing a preliminary upper pulling operation, but in its broader aspects is of general applicability to machines for pulling uppers on lasts.

It is a well recognized fact that under some manufacturing conditions, as for example where the upper is so cut that it is small for the last, or where the last is shaped in a peculiar manner, the best results in the pulling-over of the shoe and in the final shaping of the shoe require that the upper be pulled and stretched more or less before the shoe is presented to the pulling-over machine. By seizing the upper at the toe end of the last and pulling it lengthwise of the last the margin of the upper at the toe, if the upper is comparatively short, may be so located as to permit the toe gripper of the pulling-over machine readily to engage it when the shoe is presented to that machine, and such a preliminary lengthwise pull upon the upper also insures better results in the final shaping of the upper about the heel end portion of the last. Similarly, by seizing and pulling the upper at the opposite sides of the forepart, the margin may be more conveniently located for presentation to the side grippers of the pulling-over machine, and by thus drawing the upper down to the wood of the last back of the toe prior to the final pull at the toe and the sides a better final shaping of the forepart of the upper is insured. An object of this invention, among

others, is to provide an improved machine adapted for use in performing such preliminary pulling and stretching operations upon uppers with a view to simplifying the construction of such machines, rendering them more convenient for use, and improving the quality of the work.

A feature of the invention consists in a novel organization of means for pulling an upper preliminarily to stretch and position it on a last and for then releasing it in an unsecured condition, the machine herein shown having means for applying a pull to the upper substantially simultaneously at the toe end and at opposite sides of the shoe and for tensioning the upper variably as determined by the operator during the progress of the upper pulling operation. The illustrative construction comprises grippers for engaging the upper respectively at the toe and at opposite sides of the forepart, with treadle operated means for causing all of said grippers to close upon the upper prior to the pulling of the upper either longitudinally or transversely and for then moving the last relatively to the grippers to pull the upper to an extent variably determined by the operator in accordance with the condition of the particular shoe. The use of this construction insures that the upper shall be engaged by the grippers at the precise points desired at the sides as well as at the toe end of the last, and contributes to uniformity of results on work where the margin of the upper needs to be pulled to substantially the same extent at the toe and the sides.

A further feature of the invention consists in novel means for positioning a shoe and for applying a pull to the upper substantially simultaneously at the toe and at opposite sides, so organized as to permit the operator to vary at will the relation between the longitudinal tension and the transverse tension as the pulling of the upper progresses, thus facilitating the proper stretching and shaping of uppers which require different treatment at the toe and the sides respectively; the machine herein shown having shoe positioning means so constructed as to permit the operator to swing the shoe to proportion as desired the longitudinal pull of the toe gripper to the transverse pull of the side grippers. The construction shown also affords, as an additional feature, provision for lateral swinging movement of the last to ef-

fect a relative adjustment between the last and the upper as, for example, to straighten the tip seam, or to effect relative adjustment between the toe gripper and the opposite 5 sides of the last.

A further feature of the invention, as applied to an organization comprising a shoe rest which is moved to effect a pull on the upper, consists in novel means for causing 10 the upper to be gripped in time relation to the movement of the rest. The construction shown comprises means movable with the shoe rest in the same direction for relatively forcing the gripper jaws to closed position, 15 In the illustrative construction, moreover, yieldable means is provided whereby the upper is caused to be gripped with pressure increasing in proportion to the extent of movement of the shoe rest for effecting the 20 pull, and still another feature resides in novel means for increasing the gripping pressure on an upper in proportion to the strength of the pull.

Further features of the invention are to 25 be recognized in a novel gripper construction, in a novel provision for relative adjustment of different grippers, and in various details of construction and combinations 30 of parts, all of which will now be described with reference to the accompanying drawings and pointed out in the claims.

In the drawings.—

Figure 1 is a plan view of a machine in which the invention is embodied;

35 Fig. 2 shows the machine in side elevation;

Fig. 3 illustrates the relation of the grippers and the shoe bottom rest to the shoe during the upper pulling operation, one of 40 the side grippers being omitted and the toe gripper sectioned to reveal its interior construction;

Fig. 4 is a detail view of a portion of the gripper closing means, and

45 Fig. 5 illustrates the relation of the mechanism shown in Fig. 4 to the shoe bottom rest and the gripper closing rods.

The machine comprises a frame 2 which, in the construction shown, is particularly 50 designed to be mounted upon a work bench, the upper portion of the frame having a horizontal table portion 4 upon which are mounted a toe gripper and side grippers comprising respectively gripper casings 6 and 8 which are maintained in substantially rigid relation to the table 4 during the upper pulling operation. Projecting upwardly through a bearing in the table 4 and through a lower bearing 10 in a horizontal portion 60 of the frame 2 is a rod 12 the upper end of which is roughened for engagement with a sole or innersole upon the bottom of a last, the rod being thus constructed and arranged to provide a bottom rest for the shoe. As 65 shown in Fig. 3, the bottom rest is arranged

in such relation to the grippers as to engage the bottom of the shoe at the forepart only, while leaving the shoe free to be swung vertically or moved laterally in relation to the rest and the grippers. A spring 14 mounted 70

upon the rod 12 is arranged to bear at its upper end against the table 4 and at its lower end against a bracket 16 secured to the rod, the spring thus holding the rod normally in its lowermost position determined 75 by engagement of the bracket 16 with the stationary bearing 10. In order to cause the rod 12 to elevate the shoe, the machine is provided with a lever 18 pivoted on the frame with one arm bearing upwardly 80 against the lower end of the rod and with its other arm connected by means of a link 20 to a treadle, not shown in the drawings.

To each of the gripper casings is secured rigidly a gripper jaw 22, and pivoted on the 85 casing is a co-operating jaw 24 for swinging movement toward and from the rigid jaw. Mounted slidably in each of the gripper casings 6 and 8 is a closing rod 26 which ex-

90 tends downwardly in parallel relation to the rod 12 and to the direction of the pull of the gripper upon the upper and carries at its upper end a bracket 28 upon which is mounted a roll 30 engaging in a slot 32 formed in a lateral extension or shank of the pivoted 95 gripper jaw 24. It will be evident by reference to Fig. 3 that the roll 30 and the slot 32 are in such relation to the gripper jaw as to cause the jaw to be swung toward the fixed 100 jaw 22 into position to grip the upper by an upward movement toward and relatively to the gripper jaws of the closing rod 26. For imparting such movement to the several closing rods the bracket 16 is provided with a forwardly extending arm 34 provided 105 with a slot 36 through which the closing rod 26 of the toe gripper extends, and with laterally extending arms 38 provided with slots 40 to receive the closing rods of the respective side grippers. Each of the closing 110 rods, as shown by Figs. 2 and 5, is reduced in diameter below the table 4 and is encircled by a spring 42 which bears at its upper end against the shouldered portion of the rod thus provided and bears at its lower 115 end upon a washer 44 which rests upon the corresponding arm of the bracket 16. Below the bracket each of the rods carries a limiting collar 46. It will be evident that in the use of this construction upward movement of the rod 12 to elevate the shoe relatively to the grippers imparts through the bracket 16 and the springs 42 closing movement to the rods 26 and to the pivoted 120 gripper jaws, and that by the compression 125 of the springs 42 the gripping pressure of the several gripper jaws upon the upper is increased in proportion to the extent of upward movement of the shoe and the resulting pull upon the upper.

In order to render the machine effective in the manner desired upon different sizes of shoes, the toe gripper is adjustable relatively to the rest 12 in directions lengthwise of a 5 shoe, the casing 6 of the gripper being flanged for sliding movement in guideways 48 on the table 4 and secured in adjusted position in any convenient manner, as for example by the use of a clamping screw 50. 10 In order to permit such adjustment of the toe gripper the table 4 is provided with a slot 52 in substantially parallel relation to which the slot 36 in the arm 34 of the operating bracket 16 extends, thus insuring co- 15 operative relation between the bracket and the gripper closing rod in different adjusted positions of the gripper. In order to provide for adjusting movement of the side grippers toward and from a shoe the side 20 gripper casings 8 are carried by arms 54 which are mounted upon upright pivots 56 on the table 4 located approximately adjacent to the toe end of the shoe. Slots 58 in the table 4 are curved substantially about the 25 pivots 56 as centers to permit the adjustment of the grippers, the slots 40 hereinbefore referred to in the bracket 16 extending in substantially parallel relation to the slots 58. Springs 60 mounted on the pivots 56 30 tend to swing the gripper carrying arms 54 inwardly toward the shoe rest, and each arm carries a pivoted spring pressed pawl 62 mounted adjacent to its handle portion 64 and arranged to engage the teeth of a rack 35 66 on the table 4. Each of the side grippers may thus be readily adjusted at the will of the operator toward or from the shoe rest independently of the other and held in adjusted position to conform to the different 40 enclosures in width and shape of different shoes. It will be evident, moreover, that the shoe engaging portions of the jaws of the side grippers incline convergently toward the toe end of the shoe in directions substantially or 45 approximately parallel to those portions of the edge of the shoe bottom which are opposite to the portions of the upper engaged by the grippers, and that as the side grippers are adjusted for shoes of different widths 50 the inclination of the jaws is likewise changed by reason of the swinging movement of the grippers about their pivots 56 to insure substantial conformity between the positions of the grippers and the shapes 55 of the different shoes.

In the operation of the machine the shoe is presented with the bottom of the forepart resting upon the upper end of the rod 12 and with the edge of the upper projecting 60 within the open jaws of the several grippers which project upward sufficiently relatively to the shoe rest to engage the margin of the upper even if the latter is cut comparatively small for the last. When the shoe has been 65 thus positioned the operator depresses the

treadle and raises the rod 12 against the tension of its spring 14. In the initial movement of the rod the bracket 16, through the closing springs 42 and rods 26, imparts closing movement to the pivoted gripper jaws 70 24 to cause the jaws to grip the margin of the upper. During the continued upward movement of the rod 12 and consequent elevation of the shoe relatively to the grippers, the upper is pulled by the grippers both 75 lengthwise and transversely over the last, the increasing compression of the springs 42 meantime causing the grippers to hold the upper with increasing pressure. As the upper pulling operation progresses, the operator is enabled, by swinging the shoe vertically about the rod 12 as a fulcrum, to increase or diminish the force of the pull of the toe gripper upon the upper relatively to the pull of the side grippers in order to 80 effect at any time a relative variation between the longitudinal and the transverse tension as conditions demand and to insure that the upper shall be pulled and stretched in the manner required at the different portions of the shoe without danger of stretching any part of the upper unduly. By a lateral swinging movement of the shoe about its point of engagement with the bottom rest, the operator is enabled also to adjust 85 the relation between the toe gripper and the opposite sides of the last, and also to effect a relative adjustment of the last and the upper for the purpose of straightening the tip seam before the shoe is subjected to the final 90 pulling-over operation.

Having stretched the upper in the manner required to insure the proper presentation of the margin to the grippers of the pulling-over machine and to conform and adjust the 105 upper preliminarily to the contour of the last, the operator may place his hand upon the shoe in such manner as to hold the upper substantially in the desired position, and by releasing the treadle he then permits the 110 grippers to be opened by reverse movement of the closing rods and the shoe rest to be returned to its starting position by the action of the spring 14. The shoe, while held in this manner by the operator, is immediately 115 presented to a pulling-over machine and pulled over and fastened in the usual manner.

Having described the invention, what I claim as new and desire to secure by Letters Patent of the United States is:

1. A machine for pulling and stretching an upper preliminarily on a last prior to the presentation of the shoe to a pulling-over machine having, in combination, shoe positioning means, a toe gripper, side grippers, and means for effecting relative movement of said shoe positioning means and grippers to apply to the untensioned upper substantially simultaneously at the toe and the 125 130

- 4 sides an upper stretching pull, said shoe positioning means being constructed to permit manual movement of the last relatively to the grippers to effect a relative variation 5 between the longitudinal tension and the transverse tension of the upper, and the machine being constructed to release the shoe after said upper pulling operation with the upper unsecured.
- 10 2. A machine for pulling and stretching an upper preliminarily on a last prior to the presentation of the shoe to a pulling-over machine having, in combination, shoe positioning means, a toe gripper, side grippers, 15 and manual means for effecting relative movement of said shoe positioning means and the grippers to apply to the untensioned upper substantially simultaneously at the toe and the sides an upper stretching pull and to tension the upper in such degree as determined by the operator during the upper pulling operation, 20 the machine being constructed to permit the operator by movement of the last to effect a relative variation between the degrees of longitudinal and transverse tension during the simultaneous pulling at the toe 25 and the sides.
- 25 3. A machine for pulling and stretching an upper preliminarily on a last prior to the presentation of the shoe to a pulling-over machine having, in combination, shoe positioning means, a toe gripper, side grippers, 30 and manual means for causing said grippers to close upon the upper and for moving the last to cause an upper stretching pull to be applied to the untensioned upper substantially simultaneously at the toe and the sides of the last, said manual means being constructed to permit movement of the last relatively to the grippers to effect a relative variation 35 between the longitudinal tension and the transverse tension of the upper during the upper pulling operation and also constructed for reverse movement at the will 40 of the operator to cause the upper to be released from the grippers in an unsecured condition.
- 40 4. A machine for pulling and stretching an upper preliminarily on a last prior to the presentation of the shoe to a pulling-over machine having, in combination, shoe positioning means, a toe gripper, side grippers, 45 means for closing said grippers on the upper at the toe and the opposite sides of the shoe prior to the pulling of the upper either longitudinally or transversely, and means for effecting relative movement of the shoe positioning means and the grippers to 50 pull the upper substantially simultaneously at the toe and the sides, said shoe positioning means being constructed to permit movement of the last for varying the longitudinal tension of the upper relatively to the trans- 55 verse tension as the upper pulling operation 60 progresses, and the machine being constructed to release the shoe after said upper pulling operation with the upper unsecured.
- 55 5. A machine for pulling and stretching an upper preliminarily on a last prior to 65 the presentation of the shoe to a pulling-over machine having, in combination, shoe positioning means, a toe gripper, side grippers, and means for effecting relative movement of said shoe positioning means and grippers 70 to apply to the untensioned upper substantially simultaneously at the toe and the sides an upper stretching pull and to tension the upper in such degree as determined by the operator during the upper pulling operation, 75 the machine being constructed to permit the operator by movement of the last to effect a relative variation between the degrees of longitudinal and transverse tension during the simultaneous pulling at the toe 80 and the sides.
- 60 6. A machine for pulling and stretching an upper preliminarily on a last prior to the presentation of the shoe to a pulling-over machine having, in combination, shoe positioning means, a toe gripper, side grippers, 85 and means for causing said grippers to close on the upper at the toe and the opposite sides of the shoe prior to the pulling of the upper either longitudinally or transversely and for 90 effecting relative movement of the shoe positioning means and the grippers to pull the upper substantially simultaneously at the toe and the sides, the shoe positioning means being constructed to permit the last 95 to be swung by the operator during the upper pulling operation to proportion the longitudinal pull to the transverse pull on the upper, and the machine being constructed to release the shoe after the upper pulling 100 operation with the upper unsecured.
- 65 7. An upper pulling machine having, in combination, shoe positioning means, a toe gripper, side grippers, and means for closing the several grippers upon the upper substantially simultaneously and for effecting relative movement of the shoe positioning means and the grippers to cause the grippers to pull the upper both longitudinally 105 and transversely, said shoe positioning means being constructed to permit the last to be swung by the operator during the upper pulling operation to proportion the longitudinal pull to the transverse pull.
- 70 8. An upper pulling machine having, in combination, shoe positioning means, a toe gripper, side grippers, and means for closing said grippers on the upper prior to the pulling of the upper either longitudinally 110 or transversely and for operating the shoe positioning means to cause the upper to be pulled by the grippers, said shoe positioning means being constructed for engagement with the shoe only at the bottom of the forepart to permit the last to be swung 115
- 75 9. An upper pulling machine having, in combination, shoe positioning means, a toe gripper, side grippers, and means for closing said grippers on the upper prior to the pulling of the upper either longitudinally or transversely and for operating the shoe positioning means to cause the upper to be pulled by the grippers, said shoe positioning means being constructed for engagement with the shoe only at the bottom of the forepart to permit the last to be swung 120
- 80 10. An upper pulling machine having, in combination, shoe positioning means, a toe gripper, side grippers, and means for closing said grippers on the upper prior to the pulling of the upper either longitudinally or transversely and for operating the shoe positioning means to cause the upper to be pulled by the grippers, said shoe positioning means being constructed for engagement with the shoe only at the bottom of the forepart to permit the last to be swung 125
- 85 11. An upper pulling machine having, in combination, shoe positioning means, a toe gripper, side grippers, and means for closing said grippers on the upper prior to the pulling of the upper either longitudinally or transversely and for operating the shoe positioning means to cause the upper to be pulled by the grippers, said shoe positioning means being constructed for engagement with the shoe only at the bottom of the forepart to permit the last to be swung 130

- in different directions by the operator for proportioning the longitudinal pull to the transverse pull or for relatively adjusting the upper and the last.
- 5 9. An upper pulling machine having, in combination, shoe positioning means, a toe gripper, side grippers, and manual means for closing said grippers substantially simultaneously on the upper and for operating the shoe positioning means to cause the upper to be pulled by the grippers both longitudinally and transversely, said shoe positioning means being constructed for engagement with the shoe only at the bottom 10 of the forepart to permit the last to be swung by the operator about said means as a fulcrum for proportioning the longitudinal pull to the transverse pull on the upper.
- 10 10. An upper pulling machine having, in combination, shoe positioning means, a toe gripper, side grippers, and means for closing said grippers on the upper prior to the pulling of the upper either longitudinally 15 or transversely and for operating the shoe positioning means to cause the upper to be pulled by the grippers, said shoe positioning means being constructed to permit the last to be swung by the operator in different directions at will as the pulling of the upper progresses.
- 15 11. An upper pulling machine having, in combination, a gripper support, a toe gripper and side grippers projecting upwardly 20 on said support and each comprising relatively movable jaws, a shoe bottom rest, and means for closing the several grippers substantially simultaneously and for moving said bottom rest upwardly to cause the upper to be pulled by the grippers while the grippers remain substantially stationary.
- 20 12. An upper pulling machine having, in combination, a gripper support, a toe gripper and side grippers rigidly mounted on said support and each comprising relatively 25 movable jaws, a rod projecting relatively to said grippers with its end portion in position to engage the bottom of a shoe presented to the grippers, and means for closing the several grippers substantially simultaneously and for moving said rod lengthwise to cause the upper to be pulled by the grippers.
- 25 13. An upper pulling machine having, in combination, a shoe bottom rest, toe and side grippers each comprising relatively movable jaws, means for operating said bottom rest to cause the upper to be pulled by the grippers, and means operatively connected to the bottom rest for movement with it in substantially the same direction to force the gripper jaws relatively to closed position on the upper at the toe and the sides of the 30 shoe.
- 30 14. An upper pulling machine having, in combination, a gripper support, toe and side grippers mounted on said support and each comprising relatively movable jaws, a shoe bottom rest, means for imparting operative movement to said bottom rest to cause the upper to be pulled by the grippers, and means carried by said bottom rest and movable with it to force the gripper jaws relatively to closed position on the upper.
- 35 15. An upper pulling machine having, in combination, a gripper support, toe and side grippers mounted on said support and each comprising relatively movable jaws, a rod projecting relatively to said grippers with its end portion in position to engage the bottom of a shoe presented to the grippers, means for moving said rod lengthwise to cause the upper to be pulled by the grippers, gripper operating means carried by 40 said rod, and connections between said operating means and the grippers to cause the gripper jaws to be moved relatively to closed position by the thrust of said operating means.
- 40 16. An upper pulling machine having, in combination, a shoe bottom rest, toe and side grippers each comprising relatively movable jaws, means for operating said bottom rest to cause the upper to be pulled by the grippers, an operating member movable with said bottom rest, and yielding connections between said member and the grippers to cause the gripper jaws to be forced relatively to closed position by the thrust of 45 said member.
- 45 17. An upper pulling machine having, in combination, a toe gripper, side grippers, a shoe bottom rest, means for operating said bottom rest to cause the upper to be pulled by the grippers, a bracket movable with said bottom rest and constructed to present portions in substantial alignment with the respective grippers, and connections between said bracket and the grippers for 50 forcing the gripper jaws relatively to closed position.
- 50 18. In an upper pulling machine, the combination with a shoe bottom rest, of toe and side grippers each comprising relatively movable jaws, closing members movable toward said jaws to force them relatively to closed position, means for operating said bottom rest to cause the upper to be pulled by the grippers, and means 55 movable with the bottom rest in substantially the same direction for operating said closing members.
- 55 19. In an upper pulling machine, the combination with a shoe bottom rest, of an upper engaging gripper comprising relatively movable jaws, means for operating said bottom rest to cause the upper to be pulled by the gripper, and means movable with said bottom rest in the same direction.

tion for forcing one of the gripper jaws into closed relation to the other jaw.

20. In an upper pulling machine, the combination with a shoe bottom rest, of an upper engaging gripper comprising relatively movable jaws, means for operating said bottom rest to cause the upper to be pulled by the gripper, an operating member movable with said bottom rest in the same direction, and a yielding connection between said member and the gripper to cause the jaws to be moved relatively by the thrust of said member to close them.

21. In an upper pulling machine, the combination with a shoe bottom rest, of an upper engaging gripper comprising relatively movable jaws, means for operating said bottom rest to cause the upper to be pulled by the gripper, a closing member movable toward the gripper jaws to cause them to grip the upper, and means connecting said closing member to the bottom rest for operating said member.

22. In an upper pulling machine, an upper engaging gripper comprising relatively movable jaws, a shoe bottom rest, means for moving said bottom rest to cause the upper to be pulled by the gripper, a closing rod projecting from the gripper and movable toward the gripper for forcing the jaws relatively to closed position, and means movable with said bottom rest for operating said closing rod.

23. In an upper pulling machine, the combination with a shoe bottom rest, of an upper engaging gripper comprising relatively movable jaws, means for operating said bottom rest to cause the upper to be pulled by the gripper, a closing member movable toward the gripper jaws to force them relatively to closed position, and yielding means connecting said member to the bottom rest for operating said member.

24. In an upper pulling machine, the combination with a shoe bottom rest, of an upper engaging gripper comprising relatively movable jaws, means for operating said bottom rest to cause the upper to be pulled by the gripper, a closing rod movable toward the gripper jaws to cause them to grip the upper, a spring on said rod, and a connection to the bottom rest for operating the closing rod through said spring.

25. In an upper pulling machine, the combination with a shoe bottom rest, of an upper engaging gripper comprising relatively movable jaws, means for operating said bottom rest to cause the upper to be pulled by the gripper, a closing rod movable toward the gripper jaws to cause them to grip the upper, a bracket movable with said bottom rest and through which said rod extends, and a spring pressing at one end on said rod and bearing at its other

end on said bracket for transmitting operative movement from the bracket to the rod to cause the jaws to grip the upper.

26. In an upper pulling machine, a support for a pair of gripper jaws, a jaw fixed on said support, a co-operating jaw pivotally mounted directly on said support, and a closing member movable toward said jaws to swing the pivoted jaw toward the fixed jaw.

27. In an upper pulling machine, a gripper comprising relatively movable jaws, a closing member movable bodily toward and from said jaws relatively to the jaws, means for causing said jaws to be moved relatively to closed position by the thrust of said member upon a movement of the member toward the jaws, and yielding means on the member for imparting gripper closing movement to said member.

28. In an upper pulling machine, a support for a pair of gripper jaws, a jaw fixed on said support, a co-operating jaw pivotally mounted directly on said support, and a closing member having a pin and slot connection with the pivoted jaw and movable toward said jaws to impart closing movement to the pivoted jaw.

29. In an upper pulling machine, a gripper comprising a casing, a jaw fixed on said casing, a co-operating jaw directly mounted on the casing to swing toward and from said fixed jaw, a closing rod movable in the casing toward and from the jaws, and means carried by said rod for swinging the movable jaw toward the fixed jaw upon a movement of the rod toward the jaws.

30. In an upper pulling machine, a gripper comprising a casing, a jaw fixed on said casing, a co-operating jaw directly pivoted on the casing, a closing member slideable in the casing toward and from the jaws in directions substantially parallel to the direction of the pull of the gripper, and a pin and slot connection between said closing member and the pivoted jaw for closing said jaw when the member is moved toward the jaws.

31. In an upper pulling machine, a gripper comprising relatively movable jaws, and a closing device movable bodily toward and relatively to said jaws in a direction substantially parallel to the direction of the pull of the gripper throughout the relative closing movement of the jaws and provided with a closing member in sliding engagement with one of the jaws.

32. In an upper pulling machine, a gripper comprising relatively movable jaws, and a member having a pin engaging in a slot in one of said jaws for moving it toward and from the other jaw by bodily movements of the member toward and from the jaws respectively.

33. In an upper pulling machine, a grip-

per casing, gripper jaws mounted on said casing, a closing member movable toward and from said jaws, means for effecting relative closing movement of the jaws by a 5 movement of the member toward the jaws, a closing spring, and means for imparting jaw closing movement to said member through said spring.

34. In an upper pulling machine, a grip- 10 per casing, gripper jaws mounted on said casing, a closing rod movable toward and from said jaws, means for effecting relative closing movement of the jaws by a movement of the rod toward the jaws, a spring 15 on said rod, and means for imparting operative movement to the rod through said spring.

35. An upper pulling machine having, in combination, a shoe bottom rest, an upper 20 engaging gripper, means for maintaining said gripper in a substantially stationary position, means for moving the bottom rest relatively to the gripper to cause the upper to be pulled by the gripper, and means for 25 increasing the gripping pressure of the gripper upon the upper in proportion to the extent of movement of the bottom rest.

36. An upper pulling machine having, in combination, a shoe bottom rest, an upper 30 engaging gripper comprising relatively movable jaws, means for moving the bottom rest relatively to the gripper to cause the upper to be pulled by the gripper, and a yielding connection between said bottom 35 rest and the gripper for effecting relative closing movement of the gripper jaws and for increasing the gripping pressure of the jaws on the upper in proportion to the extent of movement of the bottom rest.

40 37. An upper pulling machine having, in combination, a gripper support, grippers projecting upwardly from said support, gripper closing rods projecting downwardly from said grippers, a shoe bottom rest 45 mounted for upward movement to cause the upper to be pulled by said grippers, and connections between said bottom rest and closing rods to cause said rods to be moved upwardly to close the grippers.

50 38. An upper pulling machine having, in combination, a gripper support, grippers projecting upwardly from said support, a shoe bottom rest mounted for upward movement to cause the upper to be pulled by said 55 grippers, closing rods projecting downwardly from said grippers, closing springs on said rods, and connections between said bottom rest and the closing springs to cause the rods to be moved upwardly by said 60 springs to close the grippers.

39. An upper pulling machine having, in combination, a shoe bottom rest, an upper engaging gripper, means for moving said bottom rest to cause the upper to be pulled 65 by the gripper, a closing rod projecting from

the gripper, and a connection between said closing rod and bottom rest for operating the closing rod to close the gripper, said connection being constructed to permit the gripper to be adjusted toward and from the 70 bottom rest.

40. An upper pulling machine having, in combination, a shoe bottom rest, an upper 75 engaging gripper, means for moving said bottom rest to cause the upper to be pulled by the gripper, a bracket movable with said bottom rest, and a gripper closing rod connected to said bracket, the bracket having a slot therein to permit adjustment of the gripper and the closing rod relatively to 80 the bottom rest.

41. An upper pulling machine having, in combination, a gripper support, a gripper 85 on said support, a shoe bottom rest, said gripper being adjustable on the support toward and from the bottom rest, means for operating the bottom rest to cause the upper to be pulled by the gripper, and an adjustable connection to said gripper for closing it through the movement of the bottom rest in 90 different adjusted positions of the gripper.

42. An upper pulling machine having, in combination, a gripper support, grippers on said support having guideways to permit the grippers to be adjusted relatively to the bottom rest, means for operating said bottom rest to cause the upper to be pulled by the grippers, and connections for closing said grippers comprising a bracket movable with the bottom rest and having slots corresponding to the slots in the gripper support for maintaining operative relation to the grippers 95 in their different adjusted positions.

43. In an upper pulling machine, the 105 combination with shoe positioning means, of grippers for engaging the upper at opposite sides of the shoe, and supports for said grippers extending rearwardly along the shoe and mounted to swing about axes located approximately at the toe end of the shoe for adjustment to position the grippers relatively to each other for shoes of different widths and in different angular relations to each other conformable to the differences in shape of the different shoe. 110

44. In an upper pulling machine, the combination with shoe positioning means, of grippers for engaging the upper at opposite sides of the shoe, said grippers being 120 mounted to swing toward and from each other about axes substantially perpendicular to the plane of the shoe bottom, spring means tending to swing said grippers toward each other, and means for retaining 125 said grippers in adjusted position.

45. In an upper pulling machine, the combination with shoe positioning means, of grippers for engaging the upper at opposite sides of the shoe, said grippers being 130

mounted to swing toward and from each other about axes transverse to the plane of the shoe bottom, spring means for swinging each gripper in one direction, and pawl and 5 ratchet mechanism for holding each gripper in adjusted position against the tension of said spring means.

46. In an upper pulling machine, the combination with shoe positioning means, 10 of grippers for engaging the upper at opposite sides of the shoe, a support for each

gripper mounted to swing about an axis transverse to the plane of the shoe bottom to adjust the gripper relatively to the shoe, a spring for swinging said support in one 15 direction, and mechanism for retaining the support in different adjusted positions against the tension of said spring.

In testimony whereof I have signed my name to this specification.

ELI BROTHERS.
